UNITED STATES PATENT OFFICE.

HENRY ENGAU, OF NEW YORK, N. Y.

STAMPING PRESS.

Application filed November 15, 1920. Serial No. 424,006.

To all whom it may concern:

Be it known that I, HENRY ENGAU, a citizen of the United States of America, residing at New York, N. Y., have invented 5 a new and useful Stamping Press, of which the following is a specification.

My invention relates to a stamping press, and is particularly adapted for stamping letters, characters, dies, etc., in gold, silver 10 or aluminum foil on book covers, leather goods in general, such as wallets, bags, and all articles made of leather, book cloths, silk, etc.

It is an object of my invention to provide 15 a stamping press in which the operating members are all positioned within easy reach of the operator.

It is a further object to provide a machine 20 in which the downward limit of the stamping stroke of the stamping head may be accurately and easily pre-determined.

And in general, the object is to provide a very serviceable and convenient press for 25 performing work as above described.

In the preferred form of my invention, 30 there is provided a main frame and platen for supporting the operative parts of my machine. A head carrier is supported from the frame, and a stamping head is mounted 35 for movement on said head carrier. A lever is provided for actuating the stamping head, and anti-friction means may be interposed between the operating lever and the head. Adjustable means are provided for permitting 40 the downward limit of the stroke of the head to be accurately pre-determined.

In the illustrative form shown in the drawings:

Figure 1 is a side elevation of a stamping 45 press showing features of the invention.

Fig. 2 is a section taken in the plane of the line 2—2 of Fig. 1.

Fig. 3 is an enlarged fragmentary detail 50 view of a means for moving a stamping head.

In said drawings, 5 indicates any suitable form of base or platen and standards 6—7 55 preferably four in number, are supported from the platen. Secured to the upper end of the standards 6—7 are two crossbeams 8—9 which complete the framework and provide the space or opening between the standards and beams for containing the main working parts of the press.

Supported from the beams is shown a

carrier head 10 from which a stamping head 11 may be suitably supported. In the form shown, I have provided guides 12 for securing the head 11 to the head carrier in sliding relation. A pallet for holding the 60 letters or characters 13 is removably supported from the lower end of the stamping head. The head may be provided with an aperture 14, and the pallet has a handle 15, which is positioned in the opening, and the 65 latter provides ample space for the insertion of the hand when it is desired to apply or remove the pallet from the stamping head. Any suitable means such as spring 16 may hold the pallet to the stamping head. The 70 upper end of the head is preferably inclined as indicated at 17.

A lever 18 is used to actuate the stamping head. This lever may be conveniently pivoted as at 19 to a crosshead 20 which 75 may be adjustably supported from the head carrier 10. The crosshead 20 may be provided with a slot or opening 21 in which is positioned an arm or lever 22 carrying anti-friction means such as a roller 23. 80 Means such as the pivot pin 24 of the roller may secure the lever 18 and 22 together, or the arm 22 may be dispensed with and the roller carried directly by the lever 18.

A screw 25 carrying a gear 26 passes 85 through the head carrier 10 and engages the crosshead 20 for moving the latter up or down. Cooperating with the gear 26 is a gear 27 supported from the shaft 28 and any suitable means such as the hand-wheel 90 29 may be provided for rotating the gears 27—26 and adjusting the crosshead 20 up or down. Means are provided for constantly urging the stamping head upwardly, the means shown in the preferred form consisting of a bar 30 secured to the standard 95 7 at one end, and having the other end 31 engaging the upper edge of the opening 14 in the stamping head, and a spring such as 32 draws upwardly on the bar 30, and consequently urges the head 11 upwardly.

In order to heat the pallet to secure a better impression on some classes of goods, a burner 33 may be secured to the lower end of the stamping head in order to heat the 105 type or characters.

34 indicates any suitable type of supporting device or holder for the work 35, and suitable guides 36 may be provided for positioning the device in the desired location. 110

The operation of my machine is as follows:—

The article to be stamped is secured in the vise 34 and positioned in the proper location beneath the stamping head. The pallet is heated by means of the burner 33 or otherwise. The handle 18 is then drawn toward the left as viewed in Fig. 2, and the roller riding upon the surface 17 depresses the head until a line joining the points 19 and 24 is normal to the surface 17, after which continued movement to the left would permit the stamping head to rise. By means of the hand-wheel 29 within convenient reach of the operator, the crosshead 20 may be adjusted, and the downward limit of the stamping head may be accurately predetermined. It will thus be seen that with proper adjustment of the crosshead nothing is left to the sense of touch of the operator in performing the stamping operation, since the lever may be drawn entirely across the machine without moving the stamping head beyond the predetermined position.

It will be noted that I have provided a stamping press in which all of the operating elements are positioned within convenient reach of the operator, and one in which but little is left to the sense of touch of the operator.

While I have described in detail a specific form of my invention, I do not wish to be limited to the specific form shown, for various changes and modifications may be made, all within the scope of the appended claims.

I claim:

1. In a machine of the character described, a frame, a head carrier supported by said frame, a stamping head carried by said head carrier and carrying stamping characters, an adjustable crosshead carried by said head carrier, a lever pivotally mounted on said crosshead, a roller secured to said lever and

movable therewith for cooperation with said stamping head, and means for adjusting said crosshead.

2. In a stamping press, a head carrier supported from a frame, a stamping head carried by said carrier, a pallet removably carried by said head, means carried by said stamping head for heating said pallet, and anti-friction means for moving said head.

3. In a stamping press, a head carrier supported from a frame, a stamping head movable on said carrier, a lever pivoted adjacent said stamping head and a roller carried by one of said two last mentioned members and co-operating with the other of said two members for moving the stamping head when the lever is actuated, said lever serving to move the head in one direction when the lever is moved in one direction, and serving to permit the head to move in the opposite direction when the movement of the lever in the first mentioned direction is continued.

4. In a stamping press, a frame having an opening therein, a head carrier supported from said frame, a head movable on said carrier, a lever pivotally mounted adjacent said carrier and movable in the opening in said frame, a roller movable with said lever for actuating the head and manual means for adjusting the pivotal mounting of said lever, said manual means being positioned in the opening in said frame.

5. In a stamping press, a frame, a head carrier supported from said frame, a stamping head movable on said head carrier, a crosshead mounted on said head carrier, a lever carrying a roller mounted on said crosshead, a screw for moving said crosshead, a pair of gears cooperating with said screw, and a handle secured to one of said gears and positioned within easy reach of an operator for adjusting said crosshead.

HENRY ENGAU.
